ABSTRACT

Connecting device for forming an electrical connection with a wire or the like comprises a strip of conductive metal which is folded intermediate its ends to form a V-shaped center portion having a bight and sides. The sides are bent outwardly to define end portions extending in opposite directions. A wire receiving slot extends from the one end portion through the sides and bight of the V-shaped section and into the other end portion.

SLOTTED PLATE TYPE ELECTRICAL CONNECTIONS

This is a continuation of application Ser. No. 257,897, filed May 30, 1972, now abandoned.

BACKGROUND OF THE INVENTION

A widely used type of connecting device comprises a plate-like member of conductive metal having a wire receiving slot extending inwardly from one of its edges. The width of the slot is somewhat less than the diameter of the wire which is adapted to be connected to the device so that when the wire is moved laterally of its axis into the slot, the tines on each side of the slot are wedged outwardly in their own planes in the manner of cantilever beams. The resilient deflection of these tines provides continuing forces at the interfaces of the wire and the edges of the slot which gives rise to a high quality, low resistance electrical connection. Electrical connecting devices of this general type are disclosed in U.S. Pat. Nos. 2,501,187; 3,012,219; 3,617,983; and in numerous other issued patents which disclose specific embodiments adapted for specialized applications. It is unnecessary to strip insulation from the wire prior to insertion and for this reason, and for the additional reason that an excellent electrical connection is obtained, these wire-in-slot connecting devices are being enthusiastically received in the electrical industry.

As explained above, the simplest form of wire-in-slot connecting devices comprises a simple plate-like member having a slot extending inwardly from one of its edges. U.S. Pat. No. 3,617,983 shows an improved device in which the plate-like member is folded intermediate its ends and the slot extends into the bight of the folded member and partially into the two plate sections formed as a result of the fold. These known devices depend upon a relatively stiff spring system, the cantilever beams on each side of the wire receiving slot having relatively high spring rates and being capable of undergoing only limited elastic deflection during insertion of the wire. Because of these factors, the force required to insert the wire into the slot of the connecting device is relatively high and in addition, these devices must be manufactured under close and exacting dimensional tolerances if consistently high electrical performance devices are to be produced. Additionally, the engineer designing a wire-in-slot connecting type device in accordance with present engineering practice and accepted design criteria has only a limited choice as regards dimensions, material, and expected insertion force for the wire.

The present invention is directed to the achievement of an improved wire-in-slot type connecting device which will overcome manufacturing and application (i.e. insertion force) shortcomings of the present design. To these ends, the invention is directed to the achievement of a wire-in-slot type connecting device having a low rate and controllable spring system and having design features such that only a low insertion force is required to push the wire into the slot of the connecting device.

It is accordingly an object of the invention to provide an improved wire-in-slot type connecting device. A further object is to provide an improved wire-slot connecting device having improved spring systems for maintaining contact pressure between the wire and the edges of the slot. A still further object is to provide a wire-slot connecting device which utilizes torsional de-

flection of the connecting device as a means for establishing contact force with the wire. A still further object is to provide a wire-in-slot connecting device which need not necessarily be manufactured to extremely close or critical dimensional tolerances. A further object is to provide a wire in slot connecting device having a spring rate for establishing electrical contact which is substantially constant over a relatively wide range of deflection. A further object is to provide improved insulating housings for wire-in-slot type connecting devices.

These and other objects of the invention are achieved in preferred embodiments thereof which are briefly described in the foregoing abstract, which are described in detail below, and which are shown in the accompanying drawing in which:

FIG. 1 is a perspective view of a metallic wire-in-slot type connecting device in accordance with the invention, this view illustrating the appearance of the device 20 prior to insertion of the wire.

FIG. 2 is a view similar to FIG. 1 but showing the appearance of the device after insertion of the wire, the resilient deflection of the device being exaggerated in this view for purposes of illustration.

FIG. 2A is a view taken along the lines 2-2 of FIG. 2.

FIGS. 3 and 4 are fragmentary diagrammatic views illustrating the manner in which the edges of the slot in the connecting device establish electrical contact with the wire during insertion of the wire into the slot.

FIG. 5 is a diagrammatic side view of the connecting device illustrating two modes of stressing the connecting device.

FIG. 6 is a diagrammatic view of the area of contact of the wire in the connecting device and illustrating the fact that the contact area is enlarged in accordance with the invention.

FIG. 7 is a perspective view of an alternative embodiment of a metallic connecting device in accordance with the invention.

FIG. 8 is a perspective exploded view of a connector comprising a metallic connecting device and housing in accordance with the invention, the cap member of the housing and the metallic connecting device being exploded from the base member of the housing in this view.

FIG. 9 is a sectional side view of the wire connector of FIG. 8 showing the parts assembled to each other and showing the location of a wire inserting into the 50 connecting device.

FIG. 10 is a perspective exploded view of an alternative form of a connector which is adapted to connect the end of one wire to an intermediate portion of another wire.

FIG. 11 is a sectional side view of the wire connector of FIG. 10.

FIG. 12 is a perspective view of a multi-contact connector for connecting each one of a plurality of wires to individual conductors on a printed circuit board.

FIGS. 13-16 show alternative forms of connecting devices in accordance with the invention.

Referring first to FIGS. 1 and 2, a metallic connecting device for a single wire in accordance with the general principles of the invention comprises a metallic plate 2 which is folded intermediate its ends to form a V-shaped central portion having a bight 8 from which divergent sides 10 extend. The included angle between

the sides 10 is not critical, an angle of 60° being satisfactory for most purposes. The sides 10 are bent outwardly at 12 to provide oppositely directed end sections 14.

A wire-receiving slot 16 extends for substantially the full length of the connecting device and has a dead end in each of the end portions 14. This slot is of uniform width throughout most of its length but is enlarged as shown at 20 in the vicinity of the bight 8 to facilitate insertion of the wire into the slot. The portions of the slot 16 which extend into the end sections 14 divide each of these end sections into two plate sections 22, which function as separate torsion spring members in a manner described below.

Connecting devices in accordance with the invention can be manufactured from a variety of materials such as a suitable brass, berillium copper, or phosphor bronze and can be dimensioned to accept a variety of wire sizes. Furthermore, a properly dimensioned connecting device will accept a range of wire sizes.

When it is desired to connect the conducting core 4 of a wire 6 to the connecting device, the wire is simply positioned in alignment with, and spaced from, the slot 16 and is then moved laterally of its axis through the enlarged slot portion 20 and into portions of the slot extending along the sides 10. In the finished connection, the wire extends parallel to the end sections 14 and extends through the slot in each of the sides 10 as shown in phantom FIGS. 2 and 3.

During initial movement of the wire into the slot, the edges of the slot engage the surface of the wire as indicated diagrammatically at 24 in FIG. 3. Upon further movement of the wire into the slot, these edges 24 are forced into the insulation of the wire and the areas of contact between the wire and the edges move relatively along the wire axis so that in the finished connection, FIG. 4, the conducting core of the wire will be exposed adjacent to the sides 10 and will be in electrical contact with the edges of the slot.

The connecting device 2 is elastically deformed and stressed in several modes by the wire and this elastic deformation of the connector provides spring forces at the interfaces of the wire and the edges of the slot to maintain electrical contact between the parts. One mode of elastic deformation is produced by virtue of the fact that the wire, relative to the slot, moves the two sides of the V-shaped section in opposite directions along a slightly arcuate path relative to the bends 12 at the ends of the sides. This movement of the sides of the V-section produce moments in the sections 22 which can be considered to be centered at 13 in FIG. 2, so that the sections 22 are torsionally flexed along their lengths. This torsional effect is achieved by virtue of the fact that the outer ends of the sections 22 are fixed against rotative movement in their own planes.

The torsional deflection described above provide four separate low-rate spring systems for maintaining the contact forces between the wire and the edges of the slot and is achieved because of the fact that these slots extend into the end sections 14.

The four separate torsional spring systems are established by virtue of the fact that each of the plate sections 22 in each of the end portions 14 is independently torsionally stressed. This mode of resilient deformation in the connector is to be compared with the stiff flexibility of the cantilever type loading which is relied upon in previously known wire-in-slot connecting devices.

The torsional spring systems described above are not only the only spring effects which are obtained in accordance with the invention. Referring to FIG. 5, the movement of the wire into the slot also has the effect of introducing stresses which tend to bow the sides 10 (this bowing being exaggerated in FIG. 5 for purposes of clarity). The stresses tending to cause this bowing of the sides provide a component of contact pressure for urging the edges of the slot against the wire. Additionally, the bight 8 may be resiliently deformed to a slight extent in the manner of an inwardly flexed hairpin to further contribute to the maintenance of the contact pressure. Finally, the outward movement of the V-shaped sections and the sections 22, will give rise to some cantilever spring effect aside from the torsional stressing mode described above.

The precise contribution of the several modes of deflection to the total contact force developed cannot be determined and will, in any event, depend upon several factors which may vary, such as the size of the wire relative to the width of the slot, the nature of the material from which the connector is made, and the thickness of the stock metal. The torsional effect is the most significant stressing mode and provides the low rate spring system for maintenance of contact pressure.

From the standpoint of the engineer faced with the task of designing a particular wire-in-slot connecting device intended for use under a specific set of circumstances, the present invention offers the advantage of permitting the achievement of any one of a wide variety of end results. For example, if the connecting device must have a relatively high contact force and must have a somewhat stiff spring system (as may be required for a connecting device intended for use with solid aluminum or stranded copper wires) the connector can be manufactured from relatively hard material having a high elastic modulus and the end sections 14 can be shortened so that the torsional spring system will be a relatively stiff spring system. On the other hand, if it is desired to produce a connecting device which will undergo a substantial amount of deflection when the wire is inserted and which will have a low spring-rate which is reasonably constant over a wide range of deflection, the end sections 14 can be lengthened. The width of the slot 16 relative to the length of the end sections and the physical properties of the stock metal provides a further means of controlling the spring characteristics of the finished device. A device having a relatively low spring-rate and designed to undergo a substantial amount of deflection may be desirable when the connector is intended for use with ordinary stranded copper wire.

Under some circumstances, it may be desirable to rely upon the contact between the wire and one of the plate sections 10 for electrical contact and to rely upon the other plate section 10 primarily as a means for mechanically joining the wire to the connecting device, in other words, to provide a strain relief on the wire in order to safeguard the electrical connection between the wire and the connecting device. A connecting device having such a strain relief connection in combination with an electrical connection can be provided by making one of the end sections 14 relatively short so that a stiff spring system will be established between the side 10 which is adjacent to this short end section 14 and the wire. The other end section can be made relatively long to provide a low-rate spring system for the

mechanical connection to the wire and the strain relief effect.

The V-shape form in the connecting device of FIGS. 1 and 2 offers advantages in addition to the spring system advantages described above in that an improved stripping effect is achieved. Referring to FIGS. 3 and 4, the edges of the slot 16 contact the wire as shown at 24 immediately after the wire passes through the enlarged portion 20 of the slot in the bight 8. As the wire moves relatively further into the slot, these zones of contact 24 move relatively axially along the wire and away from each other as shown in FIG. 4. In other words, the edges of the slot 16 move axially along the wire as insertion proceeds and the insulation is skived or scraped from the surface of the wire. This method of penetrating the insulation is to be compared with the method relied upon in known wire-in-slot type connecting devices of extruding the insulation from the area of contact as the wire is forced into the slot.

It should also be noted that an increase in the contact area of the wire and slot edge interfaces is achieved by virtue of the fact that the edges of the slot extend obliquely, rather than normally, with respect to the axis of the wire. The actual extent to which contact area is increased will depend upon the included angle between the sides 10, the greater the angle, the greater the increase in contact area. An included angle of 60° will provide an increase of about 15% in the contact area which can be distinctly advantageous when it is desired to maintain a minimum stock thickness in the connecting device.

By virtue of the fact that the slot 16 extends into the end sections 14, it is impossible to force the wire against the dead ends of the slot during inserting so that it is therefore virtually impossible to damage the wire or to sever it by the application of an unduly high insertion force. This feature of the invention thus minimizes the possibility of severing of the wire or some of the strands thereof, a type of damage which may not be apparent immediately after insertion but which would result in inferior performances during use and/or failure after the repeated temperature cycling which takes place during the life of an electrical contact.

Under some circumstances, it may be desirable to form connecting devices in accordance with the invention as shown in FIG. 7 with the sides 10a extending parallel to, and against each other. This embodiment provides a shorter connecting device, other things being equal, than the previously described embodiments and achieves the improved spring effects discussed above although it does not provide the improvement in contact area or insulation stripping of the previously described embodiments.

FIGS. 13-15 show alternative forms of metallic connecting devices in accordance with the invention, all of which are torsionally deformed upon insertion of a wire in accordance with the principles discussed above. The embodiment 90 of FIGS. 13 and 14 is triangular as are the previous embodiments and has end plate sections 94 which are bent inwardly so that they abut at 96. The slots extend partially into these end sections so that the torsional effect is achieved.

FIG. 15 shows a simple L-shaped connecting device 100 having arms 100 and 102. The slot extends fully through the arm 100 and partially into the arm 102. FIG. 16 shows a channel-shaped connector 104 having a web 106 and sides 108. The slots extend into and

through the sides 108 and partially into the web 106. The sides may be formed slightly inwardly as shown so that upon insertion of the wire or wires (if one wire is inserted into each slot) the legs may be flexed slightly outwardly to add that mode of stressing to the torsional and cantilever modes.

Connecting devices in accordance with the invention can be manufactured in a variety of forms for a variety of uses. For example, the connecting device of FIGS. 10 and 11 might be provided with a terminal portion in the form of a ring tongue or the like on either of the ends 14. Alternatively, connecting devices in accordance with the invention can be provided with insulating housing as will now be described.

FIGS. 8 and 9 show a multi-wire connector 28 comprising a housing having a base 30 and a cap or closure 32. The base has a cavity 40 therein, the floor of which is recessed at 41 for the accommodation and the precise location of a metallic connecting device 34 which is in general in accordance with the principles described above. This connecting device has a flange 36 extending from one of its end portions that serves to locate it in the cavity 40 against a wall thereof. The connecting device 34 comprises three separate wire-receiving slots 25 which in turn are separated from each other by separator slots 38. The separator slots isolate the three individual connecting devices from each other so that they can behave individually upon the insertion of the wire in accordance with the considerations discussed above.

Base 30 has a laterally extending arm 42 through which openings 44 extend to the cavity 40. The cap 32 has depending flanges 46 on two opposite sides thereof which are disposed against the sidewalls of the base when the cap is positioned in the base, interengaging 30 dimple and recess means 50, 51 being provided to lock the cap in position.

The cap is additionally provided with two spaced apart legs 48 on its underside which function to push the wires extending through the opening 44 into the 40 slots in the connector device 34 and to retain the wires in the slots after insertion.

The housing of FIGS. 8 and 9, and the insulating housings described below can be manufactured from any suitable thermo-plastic such as a nylon which is relatively firm in thick sections which can be flexed in thin sections to permit the flexure of the legs 48 as shown in FIG. 9.

FIGS. 10 and 11 show a further embodiment which is adapted to form an electrical connection between the 50 end of one wire and an intermediate portion of another wire. The housing of this embodiment comprises a base 54 having a cavity 58 from which insertion bars or legs 60 extend. As with the previously described embodiment, the wires are inserted into the cavity 48 through openings 62 in an arm 64 of the housing.

The cap member 56 has depending flanges 57 which fit within the cavity 58 and the metallic connecting device 59 is mounted against the upper wall of this cap member between these flanges.

In use, the end portion of one wire is inserted through the opening 62 and the connector is moved laterally with respect to the other wire so that the other wire can move relatively through a passageway 66 until the 60 through wire is located in the other one of the openings 62. The cap member is then simply pushed downwardly as viewed in the drawing and the wires are forced relatively into the slots.

FIG. 12 shows an embodiment 70 for forming disengageable electrical connections between each of a plurality of wires and the conducting paths 71 on a printed circuit board 76. This connector 70, comprises an elongated housing 72 having a trough 74 extending inwardly from its lefthand side for reception of the printed circuit board. Trough 74 communicates with a cavity 78 which is divided into separate compartments by barrier walls, each compartment having a connecting device 80 mounted therein. Again, the connecting devices 80 are in accordance with the principles previously described and in addition, have a reversely bent contact arm 82 which extends from one of the end sections, the bight 83 of this arm being received within a recess 84 for purposes of location and positioning. The opposite end section is simply supported on the ledge 87.

The underside of the arm of each contact member is adapted to engage a conductor on the printed circuit board 76 as shown. The individual wires are connected to the connecting device by inserting them through openings 90 until they are in alignment with the wire receiving slot of the connecting device. The cap piece or cover plate 86 is then assembled to the base section 72 of the housing, this cap piece having depending legs 88 for forcing the wires into the slots of the connecting devices as previously described.

If desired, connecting devices of the type shown in FIG. 12 can be adapted to receive individual contact pins or posts rather than printed circuit boards. In such a modification, separate openings for the individual pins would be provided on the lefthand side of the connector rather than a conductor through as in the disclosed embodiment.

What is claimed is:

1. An electrical and mechanical connection between a conductor and a terminal member, said terminal member comprising a plate-like member of conductive sheet metal, said member being bent transversely of its length at a location spaced from one end thereof to define an end section and a conductor-receiving side section a wire-receiving slot extending into said conductor-receiving side section and extending for the full length of said side section and into said end section, said slot having a dead end in said end section, said conductor being wedged in, and extending transversely through, said slot in said side section only, portions of said side section on each side of said slot being flexed outwardly and away from each other to provide a first spring system maintaining edge portions of said slot in engagement with said conductor, and portions of said end section on each side of said slot being torsionally stressed in opposite rotary directions to provide a second spring system maintaining said edge portions of said slot in engagement with said conductor.

2. An electrical and mechanical connection as set forth in claim 1, said terminal member being substantially L-shaped.

3. An electrical and mechanical connection as set forth in claim 1, said terminal member having a second conductor-receiving side section and a second end section, said second side section being integral with said side section, said conductor extending through said slot

in said side section and through said slot in said second side section only.

4. An electrical and mechanical connection between a connecting device and an elongated conductor comprising:

a conductive slot metal member, said member being folded intermediate its ends and transversely of its length to the form of a V having a bight and divergent sides, said sides being transversely of the length of said member to define oppositely directed end portions extending from the ends of said sides, a conductor-receiving slot in said member extending along the length thereof, said slot having dead ends in said end portions of said member and said slot extending in both of said end portions and continuously in said sides, said slot intersecting said bight, said conductor having its axis extending parallel to said slot and extending through said slot in each of said sides only, said conductor being wedged between the opposed edges of said slot at contact locations, portions of said member on each side of said slot being resiliently flexed outwardly and away from each other in opposite directions and portions of said end portions on each side of said slot being torsionally stressed in opposite rotary directions.

5. An electrical and mechanical connection between at least two wires comprising:

a sheet metal plate-like member, said member being folded transversely of its length at a location intermediate its ends to define a V-shaped section having a bight and sidewalls which diverge from said bight, said sidewalls being bent transversely of their lengths to define end portions which extend in opposite directions from said sidewalls, two slots in said member, said slots extending from said bight through said sidewalls and into said end portions, said slots having dead ends in each of said end portions, at least portions of said slots in said sidewalls having a width which is less than the thickness of said wires,

said wires being in parallel side-by-side relationship with one wire in each of said slots, said wires each having an end portion extending through said slots in each of said sidewalls only, portions of said sidewalls on each side of each slot being elastically flexed in opposite directions by said wires, and portions of said end sections on each side of each slot being torsionally flexed by stresses transmitted from said outwardly flexed portions of said sidewalls whereby said wires are resiliently held in said slots,

housing means enclosing said plate-like member and said end portions of said wires, said housing means comprising a housing base and a housing closure, said housing base having an open-sided cavity therein, said plate-like member being disposed in said cavity, openings in said housing base communicating with said cavity, said end portions of said wires extending through said openings, said closure member being assembled to said base member and serving as a closure for said open side of said cavity,

said plate-like member being oriented in said cavity with said end portions of said plate-like member disposed against the side of said cavity which is opposite to said open side and with said bight proximate to said open side, said housing closure having a pair of spaced-apart integral legs extending therefrom, said legs being in straddling relationship to said bight and having their free ends against said wires thereby to retain said wires in said slots.
